M. L. Winn.

Shampooing Machine.

No. 96,528.

Patented Nov. 2, 1869.

United States Patent Office.

MARK L. WINN, OF SAN FRANCISCO, CALIFORNIA.

Letters Patent No. 96,528, dated November 2, 1869.

IMPROVEMENT IN SHAMPOOING-APPARATUS.

The Schedule referred to in these Letters Patent and making part of the same.

To all whom it may concern:

Be it known that I, MARK L. WINN, of the city and county of San Francisco, in the State of California, have invented a new and useful Apparatus for Shampooing or Washing the Head; and I hereby declare the following to be a full and exact description thereof, reference being had to the accompanying drawings, forming part of this specification.

The nature or essence of my invention consists in providing an apparatus, to be fully described below, by which the water or other liquid used in shampooing or washing the head is prevented from running down upon the face and neck.

In the drawings above mentioned—

Figure 1 is a side view of my apparatus applied to a head.

Figure 2 shows an elastic strap, for confining the hair, having an apron attached to it for the more complete protection of the neck and shoulders.

To form my shampooing-apparatus, a rim or bottomless pan, A, is provided, its lower edge being adapted to fit the head, as nearly as may be, below the principal part of the hair, and also a gutter or trough, B, adapted to fit the head, just below the rim A, and provided with a strap to secure it in place.

These parts A and B may be made of tin, gutta-percha, or other suitable material, and the trough B may be filled with sponge, S, or other porous substance, to absorb readily the liquid that may escape from the rim A.

This sponge should be wet before using, and the superfluous water pressed out, as it will not so readily absorb a liquid when dry.

To support and steady the rim A, I make two standards, one for each shoulder, (one shown in the drawing, marked D,) having a cross-piece, E, at the lower end to rest upon the shoulder, while the upper part passes into straps or staples, F and F', on the side of the rim A, holes being made in one or both of these straps, and also in the standard, for the purpose of connecting the rim and standard together in the proper relative positions, by means of the pin G.

Water, or soapsuds, or any shampooing liquid may be poured upon the head, within the rim A, and a brush, or mop of sponge, or other suitable material used in it to clean the head; and to discharge the liquid as well as the rinsing-water subsequently applied, a spout or short pipe, H, projects from the rim, to which a flexible tube may be connected, leading to a sink or other receptacle.

The elastic strap I should be placed around the head, and arranged to hold up the hair intended to be included within the rim previous to the application of the rim itself.

The foregoing being a description of my invention, What I claim, and desire to secure by Letters Patent, is—

The above-described shampooing-apparatus, consisting of the rim A, standards D, and trough B, substantially as set forth.

MARK L. WINN. [L.S.]
